UNITED STATES PATENT OFFICE.

WARNER KAUFMANN, OF CORONA, NEW YORK, ASSIGNOR TO FRIED, MENDELSON & COMPANY, A CORPORATION OF NEW YORK.

DESIGN FOR A TEXTILE FABRIC.

Application filed December 19, 1927. Serial No. 24,549. Term of patent 3½ years.

To all whom it may concern:

Be it known that I, WARNER KAUFMANN, a citizen of the Republic of Switzerland, and resident of the city of Corona, county of Queens, and State of New York, have invented a new, original, and ornamental Design for a Textile Fabric, of which the following is a specification, reference being had to the accompanying drawing, forming part thereof.

The figure is a plan view of a textile fabric, illustrating my new and ornamental design.

I claim:

The ornamental design for a textile fabric as shown.

W. KAUFMANN.
